COLOR PHOTOGRAPH PROCESSING UNIT

Harold G. Bergstrom, New Rochelle, N.Y., assignor to
Charles Beseler Company, Orange, N.J., a partnership

Filed Jan. 10, 1962, Ser. No. 68,255

Term of patent 14 years

(Cl. D61—1)

The FIGURE is a front perspective view of a color photograph processing unit showing my new design, the side not shown and the back of the unit being plain.

The essential features of my design reside in the portions shown in full lines in the drawing.

I claim:

The ornamental design for a color photograph processing unit, as shown and described.
